UNITED STATES PATENT OFFICE.

JAMES WITHERINGTON, OF CHAMBERSBURG, ASSIGNOR TO THE TRENTON IRON COMPANY, OF TRENTON, NEW JERSEY.

WIRE-FEEDING DEVICE.

SPECIFICATION forming part of Letters Patent No. 323,013, dated July 28, 1885.

Application filed June 3, 1884. (No model.)

To all whom it may concern:

Be it known that I, JAMES WITHERINGTON, a citizen of the United States, residing at Chambersburg, in the county of Mercer and State 5 of New Jersey, have invented a certain Improvement in Feed-Rolls for Wire, Wire Rods, and kindred products, of which the following is a specification.

My invention relates to a class of devices 10 employed for occasioning the feed or advance movement or the delivery of wire, wire or metal rods, shafting, or kindred products in metal, although the device is applicable for the feed of fibrous or textile rods, ropes, or cordage.

The object of my invention is the provision 15 of a device adapted to secure the accurate and certain advance of wires or wire rods, either of different sizes or of varying and irregular 20 diameters. These objects I attain by mechanism a preferred form of a convenient embodiment of which is represented in the accompanying drawings, and explained in the following description, the particular subject-matter claimed being hereinafter definitely 25 specified.

My invention is of especial applicability in connection with a certain improved apparatus 30 for straightening wires and wire rods, for which I have executed an application for Letters Patent contemporaneously with this application. The device is, however, of general applicability wherever wires, rods, and kindred products are designed to be fed.

In the accompanying drawings, Figure 1 35 represents in top plan view, and Fig. 2 in front elevation, an apparatus conveniently embodying my improvements. Fig. 3 is a side elevation or one taken from the right hand of Fig. 2, the feed-rolls and bell-mouthed guides being represented in section on the plane of the line $x x$ of Fig. 2. Fig. 4 is a side sectional elevational detail of one of the roll-standards, section being supposed on the dotted line $y y$ 40 of Fig. 1, and sight being taken from the right-hand side of said figure.

Similar letters of reference indicate corresponding parts.

In the drawings, A represents a bed-plate, 45 upon which the roll-standards B B', which

form the housing for the rolls, are supported. a are legs upon which the bed-plate rests. The roll-standards B B' are erected in parallel planes, side by side, a suitable distance apart upon the bed-plate. They support fixed bearings b b' a horizontal transverse shaft, which I term the "lower" or "fixed" shaft, C, which projects beyond both standards, and upon its right-hand extremity, in the form shown in the drawings, is equipped with a lower feed-roll, D, and upon its left-hand extremity with a beveled crown-wheel, e, which is actuated from a beveled pinion, e', mounted upon a driving-shaft, c², suitably journaled with respect to the bed-plate.

It is obvious that motion imparted to the driving-shaft will be transmitted to the lower or fixed shaft, which carries the lower feed-roll. The upper portions of the standards are vertically slotted to receive slide-bearings e e', which carry an upper or movable shaft, C', one extremity of which projects beyond the standard and is equipped with an upper feed-roll, D', which is disposed in vertical alignment above the lower feed-roll. The feed-rolls are metal wheels of suitable dimensions, grooved, depressed, or otherwise hollowed or sunken as to their peripheries to adapt them to receive a wire, wire rod, or like product. Between the standards both the upper and lower shafts are equipped with toothed pinions F F', set to mesh, and having leaves of sufficient radial depth to permit of the separation of the pinions a certain distance without disengagement.

From the above construction it will be obvious that the upper shaft, upper toothed pinion, and upper feed-roll are adapted, by virtue of the arrangement of the slide-bearings, to be moved vertically upward and away from their corresponding lower or fixed devices. This capability for upward movement permits of the spreading apart of the feed-rolls to receive wires of different sizes, or to permit of the passage of a wire of varying diameter.

In order to retain the feed-rolls in contact with each other or with the wire fed through them, it is necessary to exert pressure upon the upper and movable shaft of the upper feed-roll, and this I accomplish by means of a cross

head or yoke, G, which straddles the standards and bears upon the slide-bearings, and by means of suspenders g g, hung upon said yoke and connected together below the bed-plate by a lower cross-head, g', which serves to receive the downward thrust of a lever, H, fulcrumed at h, beneath the bed-plate, and provided with a counter-weight, h', as shown in the drawings. The operation of this contrivance is to retain the feed-rolls in contact.

I J are bell-mouthed guides respectively in advance of and to the rear of the feed-rolls, and designed to receive the wire or rod to be fed and respectively conduct it to the rolls and from the rolls out to the machine in which it is to be manipulated or the reels upon which it is to be wound.

It is obvious that other contrivances than the suspenders, cross-heads, lever, and weight can be substituted for the purpose of retaining the feed-rolls in contact; but I prefer the contrivances represented to others, many of which would be obvious to any mechanician.

It will also be understood that two, or a series of sets of, feed-rolls may be arranged in succession and geared from the driving-shaft, so as to all travel at an equal rate of speed.

The present arrangement of crown-wheel and pinion for driving may of course be varied, and other arrangements substituted in their stead.

Having thus described my invention, I claim and desire to secure by Letters Patent—

1. The combination, in an apparatus for feeding wire, wire rods, and kindred products, of a grooved feed-roll mounted upon and driven by a fixed axle, a second grooved feed-roll disposed in line with the first-named roll and mounted upon an axle which is movable

so as to permit the rolls to move apart from each other, means for driving the fixed roll, gearing for positively connecting the two rolls, means for retaining the movable roll in yielding contact with the fixed roll, a bell-mouthed guide for directing the wire to the feed-rolls, and a housing for containing the said appliances, substantially as and for the purposes set forth.

2. The combination of the standards, the lower shaft fixedly journaled in said standards, the lower feed-roll, the movable shaft adapted to move to and from the fixed shaft, the movable feed-roll mounted upon said movable shaft, means for driving the fixed shaft, positive gearing for connecting the two shafts, the yoke, suspenders, lower cross-head, and weighted lever for retaining the rolls in contact, substantially as and for the purposes specified.

3. The combination of the standards, the lower shaft fixedly journaled in said standards, the lower feed-roll, the movable shaft adapted to move to or from the fixed shaft, the movable feed-roll mounted upon said movable shaft, means for driving the fixed shaft, positive gearing for connecting the two shafts, the yoke, suspenders, lower cross-head, and weighted lever for retaining the rolls in contact, and a bell-mouthed guide for directing the wire into the bite of the rolls, substantially as and for the purposes specified.

In testimony whereof I have hereunto signed my name this 22d day of May, A. D. 1884.

JAMES WITTINGTON.

In presence of—

J. BONSALL TAYLOR,
W. C. STRAWBRIDGE.
